TO HUBERT E. WILCOX, OF INDIANAPOLIS, INDIANA.

ELCTROTHERMOSTATIC CONTROLLER.

1,223,117.

Specification of Letters Patent.

Patented Apr. 17, 1917.

Application filed September 16, 1916. Serial No. 120,506.

To all whom it may concern:

Be it known that we, JOSEPH C. SCHAF, Jr., and WILLIAM E. MUNK, citizens of the United States, and residents of Indianapolis, county of Marion, and State of Indiana, have invented a certain new and useful Electrothermostatic Controller; and we do hereby declare that the following is a full, clear, and exact description thereof, reference being had to the accompanying drawings, in which like letters refer to like parts.

This invention relates to an electric controller or electrothermostatic heat regulator which will make or break an electric circuit 15 so as to control the heat caused by the resistance therein. Such a controller is especially adapted to be used in connection with electrically heated articles where it is necessary to keep the article at a substantially 20 uniform temperature, such as electric heating pads, irons and the like.

The main feature of this invention resides in a regulating means for so adjusting the thermostatic bar that it will make and break 25 a circuit substantially at a given temperature.

Another feature of the invention is the provision of a dial indicating means whereby the contact point may be regulated so as 30 to more specifically control the temperature.

A further feature of the invention is in the construction of the resistance coil box whereby no core is necessary and the construction is greatly simplified.

The full nature of this invention will be understood from the accompanying drawings and the following description and claims:

Figure 1 is a plan view of the instrument. Fig. 2 is a cross section through the line 2-2 of Fig. 1. Fig. 3 is a plan view of the bottom side of the instrument with the lower covering removed. Fig. 4 is a plan view of the instrument with the top covering removed and showing the electrical wiring thereof. Fig. 5 is a cross section through line 5-5 of Fig. 1.

In the drawings there is shown an electrothermostatic heat regulator comprising a box or covering having an upper lid or top 10 and a box like casing 11. Secured to the lid 10 there is a block 12 having a central longitudinal recess 13 therein. Said block is secured to the lid or covering by means of the bolts 14 extending downwardly

therethrough. Secured in said recess 13 there is a resistance coil 15 which extends through openings at each end of said recess so that one end thereof terminates in a contact screw 16 while the other end terminates in a contact screw 17. The screw 16 passes through a metal plate 117 so as to make electrical contact therewith, while the screw 17 is the terminal for the wire 18 which leads from any suitable source of 65 electricity. Therefore, the current passes through the plug 41 conducting wire 18 and the screw 17 thence through the extension 19 of coil 119 to said coil and thence through 116 to screw 16 to plate 117. 70

There is a thermostatic bar 19 composed of two layers of metal secured together having different co-efficients of expansion. Said bar is rigidly secured to one end of the block 12 by the screws 20 and 21. The other end 75 of the bar is free to move and has a contact point 22, preferably of platinum, said point being in position to make contact with the platinum point 23 which is on the end of an adjusting screw 24 which is raised or 80 lowered with reference to the plate 17 by a thumb screw 25 by means of which said screw is turned. Said thumb screw is provided with a pointer 26 which registers on a dial 27. 85

The wire 28 leads from the other terminal of the plug 41 directly through the box or casing in a groove 29 of the block 12 and passes out at the other end. The wire 30 is electrically connected to the screw 21, which is at all times in contact with the thermostatic bar 19, whereby a circuit is completed through bar 19, points 22 and 23, plate 117, screw 16, extension 116, coil 15, extension 119, screw 17 and wire 18. 90 95

The bar 19 is normally in contact with screw 24 so that a circuit is made. The current then necessarily passes through the resisting coil 15 which is heated thereby, causing the metals in the bar 19 to expand in 100 different degrees, thereby breaking the contact at points 22 and 23 so that the circuit will be broken. As soon as the resistance coil permits the bar to be cooled sufficiently to be returned to its normal position and 105 make contact, the circuit will be again made until sufficient heat is regenerated for the expansion of the bar. It will, therefore, be readily seen that there is a making and breaking of the circuit which permits only 110

enough current to pass through the circuit to maintain the article 40 to be heated at substantially uniform temperature.

Secured to said block 12 over the bar 19 there is an upwardly and forwardly extending arm 31 through which an adjusting screw 32 extends so as to bear against said bar and adjustably regulate the relative position of the contact points 22 and 23. By 10 this regulating means the bar is adjusted so as to operate roughly between certain degrees of temperature. After bar 19 has been properly adjusted by screw 32 further adjustment of the regulation and control of 15 the temperature may be made by the thumb screw 25 which further regulates the relative positions of points 22 and 23.

The invention claimed is:

1. An electric controller having an insulating block with a recess therein, a resistance coil in said recess, a terminal secured to one end of said block and connected with one end of said coil, a thermostatic bar secured at one end to the other end of said block, 25 the free end portion of said bar normally making contact with the said terminal and thereby connecting the bar and coil in the series, and means secured to said bar for limiting the movement thereof.
2. An electric controller having an insulating block with a recess therein, a resistance coil in said recess, a terminal secured to one end of said block and connected with one end of said coil, a thermostatic bar secured 35 at one end to the other end of said block, the free end portion of said bar normally making contact with the said terminal and thereby connecting the bar and coil in the series, an arm rigidly secured on the fixed 40 end of said bar and extending upwardly therefrom, and a screw extending through said arm for engaging said bar and limiting the separating movement of said bar and its contact point from said terminal.
3. An electric controller having a solid block of insulating material provided with a recess therein, a resistance coil in said re-

cess, a metal plate secured to one end of said block and connected with one end of said coil, and a thermostatic bar rigidly secured to one end of said block, the free end portion of said bar being normally in contact with said plate, thereby connecting the bar and coil in series.

4. An electric controller having a solid block of insulating material provided with a recess therein, a resistance coil in said recess, a metal plate secured to one end of said block and connected with one end of said coil, a thermostatic bar rigidly secured to one end of said block, the free end portion of said bar being normally in contact with said plate, thereby connecting the bar and coil in series, and an adjusting screw passing through said block and adjustable through 65 said plate having a contact point thereon whereby the distance between said last mentioned contact point and said bar may be regulated.

5. An electric controller having a solid insulating block with a recess therein, a resistance coil in said recess, a metal plate secured to one end of said block and connected with one end of said coil, a thermostatic bar rigidly secured at the other end to 75 said block, the free end portion of said bar being normally in contact with said plate, thereby connecting the bar and coil in series, an arm secured to the fixed end of said bar extending thereover, a screw extending 80 through said arm adapted to engage and adjust the position of said bar, and a controlling screw extending through the other end of said block adapted to screw through said plate and having a contact point thereon 85 adapted to regulate the distance between said contact point and the free end of said bar for controlling the amount of heat generated by said coil for breaking said contact.

In witness whereof, we have hereunto af- 90 fixed our signatures.

JOSEPH C. SCHAF, JR.
WILLIAM E. MUNK.
